DESIGN FOR A PAIR OF SPECTACLES

Roger L. McCracken, Chili, N.Y., assignor to Bausch & Lomb Incorporated, Rochester, N.Y.

Filed Sept. 23, 1969, Ser. No. 19,260

Term of patent 14 years

Int. Cl. D16—08

U.S. Cl. D57—1

FIG. 1

FIG. 2

FIG. 3

FIG. 1 is a front view of a pair of spectacles showing my new design;

FIG. 2 is a side view of said spectacles taken from the right side thereof as viewed in FIG. 1;

FIG. 3 is a top plan view thereof.

The side not shown has substantially the same appearance as the side shown.

The temples are broken away in FIG. 3 for convenience of illustration.

The characteristic features of my design reside in the specific configurations of the temple-engaging portions of the frame, in combination with the lens and bridge configurations, as best seen in FIG. 1.

I claim:

The ornamental design for a pair of spectacles, substantially as shown and described.
